UNITED STATES PATENT OFFICE.

BENJAMIN N. BROIDO, OF NEW YORK, N. Y., ASSIGNOR TO THE SUPERHEATER COMPANY, OF NEW YORK, N. Y., A CORPORATION OF DELAWARE.

BOILER CONSTRUCTION.

Application filed April 1, 1925. Serial No. 18,807.

In the construction of the well known Stirling type water tube boilers, having a plurality of separate banks or passes of water tubes of equal diameter, it is the standard practice to provide the same number of tubes in each transverse row throughout all the passes, and to arrange the tubes in each transverse row in pairs. The space between adjacent pairs is just sufficient to allow the ready removal or replacement of a tube at any part of the boiler, while the space between the tubes of each of said pairs is much more restricted.

As the modern development of the steam boiler is towards the general adoption of superheat much higher than heretofore employed, it becomes necessary to place the superheater units comparatively close to the furnace and preferably between the water tubes of the first bank but because of the restricted space between the water tubes of the Stirling type of boiler, the use of high superheat with this type of boiler presents many difficulties among which the following may be noted: in the first place, the mechanical difficulties in assembling and installing; secondly, after the superheater is installed, the restriction of the gas area; thirdly, the tendency of flue dust and ashes to collect in the spaces between the superheater units and water tubes and thereby impair the efficiency of the boiler; and fourthly, the impracticability of increasing the spacing between the tubes which would result not only in unduly increasing the gas area, but would require a much larger floor space for the boiler and also greatly increase the cost of manufacture.

It is the principal object of this invention to provide a new and improved construction and arrangement of a Stirling type boiler by means of which the difficulties above enumerated are overcome.

Other more specific objects will be apparent to those skilled in the art to which this invention relates from the following description.

In the drawings which illustrate an example of my invention without defining its limits, Fig. 1 is a vertical section through a water tube boiler of the Stirling type and Fig. 2 is a section taken substantially on the line 2-2 of Fig. 1 looking in the direction of the arrows.

As shown in the drawing, the boiler indicated generally by the numeral 10 is provided with a furnace 11 from which the gases flow through the boiler to the outlet 12, which is adapted to be connected with a suitable stack. In accordance with the usual constructions of boilers of this type, a plurality of banks or passes 13, 14 and 15 of water tubes extend in a substantially vertical direction and connect the upper steam drums, 16, 17 and 18 with the lower water drum 19; baffle walls 20 and 21 being provided to cause the gases to flow across the tubes in the longitudinal direction thereof. As shown in Fig. 2, the spacing of the tubes in each of the banks 14 and 15 is similar; each of said banks being provided with an equal number of rows of tubes transversely of the boiler in accordance with the standard practice. The spacing of the tubes of the front bank 13 is greater than in the remaining banks, this being accomplished by providing a smaller number of tubes in the transverse rows of said front bank. In the example illustrated, 24 rows of tubes are provided in each of the banks 14 and 15, while only 20 rows are provided in the bank 13. By eliminating a number of rows of water tubes in the first bank 13 I am enabled to provide sufficient space between the tubes to permit the installation of the superheater units 23 without crowding the tubes and units too close together, thereby overcoming the difficulties enumerated above, while at the same time the overall width of the boiler is not increased and the effective area of the gas passage in the first pass is maintained substantially the same as the effective area of the gas passage of each of the remaining passes. By the "effective area of gas passage" is meant the area of that part of a plane passing perpendicularly to the axis of the tubes which is bounded by lines drawn tangentially to the outer wall of the four outside rows of tubes of each bank, deducting from such area of the plane so bounded, the combined cross-sectional area of the boiler tubes and superheater elements which pass through said plane.

As there is a marked tendency towards the adoption of boiler pressures many times higher than those heretofore generally employed, the problems due to the great stress placed upon the drums, and particularly the

2
drums of the first bank which are subjected to temperatures sufficiently high to affect the strength of the drum material, become quite difficult. The construction herein disclosed, because of the greater space provided between the tubes of the first bank, thereby increasing the size of the ligament between the tube apertures in the drum, and the protective influence of the superheater units interposed between said tubes, therefore possesses the further advantage over the standard construction of being exceptionally suitable for super-pressure boilers.

It will be understood that the number of rows and the arrangement of the tubes in each bank as shown in the drawings is merely illustrative and that changes, variations and modifications may be resorted to without departing from the spirit of my invention.

I claim:

1. In a water tube boiler, a furnace, said boiler having a plurality of banks of water tubes located at different distances from said furnace, the first bank of tubes nearest to the furnace having a smaller number of rows of tubes transversely of the boiler spaced apart at greater distances than the remaining banks, and a plurality of superheater units extending downwardly into the boiler between the tubes of the first bank, the effective area of the gas passage formed in said first bank between the superheater units and the water tubes of said bank being no less than the effective area of the gas passage of each of the remaining passes.

2. In a water tube boiler of the Stirling type, a furnace and a plurality of banks of water tubes located at different distances

from said furnace, each of said banks of tubes comprising a plurality of rows of tubes arranged in non-staggered parallel relationship and spaced transversely to permit the removal of tubes between certain adjacent rows, and a plurality of superheater units extending downwardly into the boiler between the tubes of the first bank nearest to the furnace, the tubes of said first bank being similarly spaced throughout the entire bank but at greater distances apart than in the remaining banks to provide sufficient space between said superheater units and tubes to avoid unduly restricting the effective passage for the furnace gases and clogging of flue dust and ashes between said units and tubes.

3. In a water tube boiler of the Stirling type, a furnace and a plurality of banks of water tubes located at different distances from said furnace, each of said banks of tubes comprising a plurality of rows of tubes arranged in non-staggered parallel relationship and spaced transversely to permit the removal of tubes between certain adjacent rows, and a plurality of rows of superheater units extending downwardly into the boiler in the transverse spaces between adjacent parallel rows of tubes of the first bank nearest to the furnace, the tubes of said first bank being similarly spaced throughout but at greater distances than in the remaining banks, there being a clear space between the furnace and those superheater units of each row which are nearest the furnace.

In testimony whereof I have hereunto set my hand.

BENJAMIN N. BROIDO.
